DISPLAY CARD FOR PACKAGED MERCHANDISE

William Albert Binstead, 106 Old Farm Road S.,
New Hyde Park, N.Y.

Filed Nov. 8, 1965, Ser. No. 88,041

Term of patent 14 years

(Cl. D80—5)

FIG. 1

The dominant features of my design reside in the portions shown in full lines.

I claim:

The ornamental design for a display card for packaged merchandise, as shown and described.
